JOHN G. MORRISON, OF NEW YORK, N. Y.

MOLDING-MACHINE.

No. 906,259.

Specification of Letters Patent.

Patented Dec. 8, 1908.

Application filed January 4, 1908. Serial No. 409,341.

To all whom it may concern:

Be it known that I, JOHN G. MORRISON, a citizen of the United States, and a resident of the borough of Brooklyn, in the city of New York, county of Kings, and State of New York, have invented certain new and useful Improvements in Molding-Machines, of which the following is a specification.

My invention relates more particularly to 10 that form of molding machine which is employed in foundries for making molds in sand from patterns of the various articles that it is desired to cast, although it is obvious that it may be otherwise employed for making 15 molds for other purposes; the object of the invention being, to provide a machine of this character, which, while extremely simple in construction and efficient in operation, shall, at the same time, make the desired 20 molds automatically and continuously, without necessitating the employment of skilled labor in the operation.

To these ends the invention consists, first, in various constructions and combinations of 25 parts, of which the particular forms preferred in practice will be first described, and the novel features of the invention then pointed out in the subjoined claims.

Referring to the accompanying drawings, 30 which form a part of this specification, Figure 1, is a longitudinal sectional view of a machine constructed in accordance with my invention, taken generally in the line $x-x$ of Fig. 2, with various of the parts shown in 35 side elevation and others broken away for convenience of illustration; Fig. 2, a transverse sectional view of the same, taken generally in the line $y-y$ of Fig. 1, with various of the parts shown in side elevation; Fig. 3, a 40 reverse plan view of the machine showing more particularly the mechanism employed for connecting and operating the various parts thereof; Fig. 4, a side elevation of a fragment of one of the gear wheels employed 45 for moving the flask holding and carrying carriers beneath the sand supplying and compacting mechanism, and Fig. 5, a detached detail, showing the manner of clamping the flasks to the carrier.

50 In all the figures, like letters of reference are employed to designate corresponding parts.

A indicates the bed or platform upon and from which the various parts of the machine 55 are supported, and B and B^1 respectively in-

dicate the flasks in which the molds for the various articles to be cast are formed.

The bed or platform A is or may be constructed in any approved form, and is or may be supported upon suitable legs or piers, or 60 rest upon the floor of the building in which the machine is located, with a pit or cellar beneath for the accommodation of the operative parts of the structure that are arranged beneath the bed or platform, as may be required or as the exigencies of the use of the machine may demand. In the form of the invention shown in the drawings however, it is constructed in plate form of the required 65 dimensions, and is provided on its upper surface at the required point with pairs of parallelly disposed rails a and a^1 , upon which are caused to travel the carriers C and C^1 , upon 70 which the flasks B and B^1 are respectively carried.

75 Mounted upon the body or platform A is a hopper D to which the sand to be used in the molding operation is supplied, and through which it is fed to the flasks B and B^1 , as they are caused to travel back and forth beneath 80 it on their respective carriers C and C^1 . This hopper may be constructed in various forms. It is preferred however to construct it of a cylindrical tubular contour, with its bore of the proper diameter to extend outward over 85 both of the flasks and with its upper end outwardly flared, as shown in the drawings. As thus constructed, this hopper is arranged directly over the paths of travel of the flasks B and B^1 , with its lower end in close relation- 90 ship to their upper surfaces, in which position it is fixedly held through appropriate means from the bed or platform A. In my preferred form of construction these supporting means consist of stands d , supplemented 95 by a platform E, which is provided with a suitable opening e formed therein through which the upper end of the hopper D is passed and firmly held. Of these, the stands d are respectively secured at their upper and 100 lower ends to the lower end of the hopper D and to the bed or platform A, by screws or bolts d^1 , while the platform E is supported above the bed or platform A by stands e^1 , which, in turn, are respectively secured at 105 their upper and lower ends to the platform E and to the bed or platform A by screws or bolts e^2 .

Within the hopper D, as thus supported, is arranged the compacter F by means of 110

which the feeding of the sand downward through the hopper and its compacting within the flasks are effected. This compacter, which is preferably located in the lower end 5 of the hopper in close relationship to the top of the flasks B and B¹ as they are passed beneath it, is fixedly secured upon a vertical shaft H, which extends downward axially through the hopper and through the bed or 10 platform A, and is rotatively mounted in bearings h and h¹, of which the bearing h is formed within a girth d², extending across the bed or platform A from one of the stands d to another, while the bearing h¹ is formed 15 in a spider e³ that is supported above the platform E through the intermediaries of stands e⁴, which are respectively secured at their upper and lower ends to the spider and to the platform by screws or bolts e⁵.

20 In the construction of the compacter F various forms may be adopted. It is preferred however to construct it in the form of a double screw, with two ribbon shaped spirally arranged flanges f extending outwardly 25 in opposite directions from a central hub f¹, and having the lower end of each lying substantially in a plane passing at right-angles through the axis of the shaft H.

With the parts constructed and arranged 30 as thus explained, the feeding of the sand downward through the hopper D will be effected by simply rotating the shaft H in the proper direction; and in order to loosen up the sand supplied to the hopper and maintain it in a loose condition while being fed 35 downward by the compacter, I find it desirable to provide the shaft H with outwardly extending blades h² which may be laterally inclined either upward or downward with respect to the direction of rotation of the shaft, or some may incline upward and others downward as may be preferred. In the drawings 40 however, I have shown these blades as disposed spirally around the shaft, with the two upper blades laterally inclined upwardly and the remaining blades downwardly, but this is merely illustrative, and other inclinations and arrangements of these blades may be adopted as may be preferred.

45 While the shaft H is thus equipped, its rotation may be accomplished through any of the ordinary and well known forms of motion transmitting devices. In the drawings however, I have shown it effected from a shaft I, 50 which, provided with a pulley L and mounted in suitable hangers i extending upward from the platform E, is connected with the shaft H through the intervention of bevel gears h³ and i¹, with which the shafts H and I 55 are respectively provided.

60 The mechanism for supplying the sand to and compacting it in the flasks being thus constructed and arranged, the carriers C and C¹, which support and carry the flasks B and B¹ beneath it to receive the sand, may be

modified in various ways. I prefer however to construct them with body portions c, which are provided on their tops with plane horizontal surfaces c¹, and to mount them on appropriate wheels c², that are adapted to 70 run upon the rails a and a¹, whereby to guide the flasks carried by them in proper relation to the hopper and compacter when moved under them.

As thus constructed and mounted the carriers 75 receive the flasks B and B¹ which rest upon their plane horizontal surfaces c¹, and upon which they may be held from lateral displacement by dowel pins c³, which extend upward from the carriers and engage with 80 suitable holes b formed in the bottoms of the flasks or otherwise. These flasks, which form no part of my present invention, are or may be of any of the ordinary or preferred constructions, and may be employed either 85 with their constituent "copes" and "drags" united, or the copes may be used alone, in either of which cases the carriers will be made of the proper heights to bring their upper edges in close relationship to the hopper or 90 compacter when carried under them.

When the flasks are employed with their copes and drags united, as when a portion of each of the molds has been formed in its appropriate drag and it is desired to form the 95 remainder of the mold in its respective copes, as ordinarily practiced in the art, the bottoms of the drags will rest upon the flat horizontal surfaces c¹ through the intervention of their respective "bottom boards", which will be 100 interposed beneath them. On the other hand, when it is desired to form the molds entirely within the copes, then the copes will be detached from their coöperating drags and their bottom edges will be placed and rest directly upon the plane horizontal surfaces c¹, which will then serve as "mold boards", in place of those ordinarily employed, and in that case the patterns b¹ will rest directly upon and may be secured to them, as shown 110 in Fig. 2.

With the flasks B and B¹ resting upon the plane horizontal surfaces c¹, whether used with their parts united, or with their copes separated from their coöperating drags, they 115 will be firmly held upon the upper surfaces of their carriers by any appropriate means. In some instances, I find it convenient to effect this holding by clamps secured to the sides of the carriers and constructed with 120 pivoted levers c⁴, having eccentric hubs formed upon their sides which engage with holes in the lower ends of links c⁵, that engage at their upper ends with appropriate flanges b³ on the flasks, through hooks c⁶ formed on 125 their upper ends, as shown in Fig. 5. In other instances, on the other hand, I find it convenient to employ for this purpose rolls d³, which are journaled in suitable bearings d⁴ formed in brackets d⁵ secured to and ex- 130

tending outward from the hopper D, and either or both of these forms of holding means may be employed as preferred. Again, in some instances but a single carrier 5 will be employed, and in such case it will be moved back and forth beneath the hopper and compacter by itself alone. I prefer however to employ a plurality of these carriers connected in trains, and to pass one 10 train beneath the hopper and compacter in one direction on one pair of rails, as, for instance, on the pair a , and to pass a second train at the same time backward under them in an opposite direction, as, for instance, on 15 the pair of rails a^1 , in which case each carrier as it passes under the hopper and compacter will have the mold of the pattern carried by it formed in its appropriate flask, which may then be removed, and an empty flask supplied in its place, when such carrier may then 20 be transferred to the other pair of rails and passed backward under the hopper and compacter in the opposite direction, with the result that at such transit a second mold will be 25 formed in that flask, and so on, each transit of a flask beneath the hopper or compacter causing a mold to be formed therein, and thereby rendering the machine practically continuous.

30 When thus employed in trains, the cars of each train will be connected by any appropriate connections, such, for instance, as by hook latches c^7 which, pivotally connected at one of their ends by pivots c^8 to one carrier, 35 will engage at their other ends with studs c^9 projecting outward from another carrier; and, in order to provide for the holding of the carriers at proper distances apart, I provide each of them at its ends with appropriate 40 buffers c^{10} , which, when the carriers are connected about the one with the other. With the carriers thus equipped with the buffers c^{10} , I find it desirable to interpose between 45 their adjacent ends blocks c^{11} , whereby to prevent the passage of the sand downward between them when passing under the hopper and compacter, while to remove all sand from the rails, as the carriers are moved over them, I find it convenient to provide the 50 carriers at their ends and at other appropriate points with downwardly extending scrapers c^{12} .

For propelling the carriers C and C' upon their supporting rails and beneath the hopper D and compacter F, various means may be adopted. I prefer however to employ for that purpose spur-gears M, M¹, M², and M³, which engage with racks c^{13} formed on or carried by the carriers, and which are operated 55 from the shaft H, to the end that their synchronous movements with respect to that of the compacter may be insured. As thus employed, these gears are preferably arranged in pairs, with the gears of one pair 60 separated the proper distances apart and

lying in one plane of rotation, and the gears of the other pair similarly separated and lying in another plane of rotation, which is or may be parallel to the first or otherwise. In the drawings however, I have shown these 70 planes of rotation as arranged in parallel relationship to each other, and as being co-incident with longitudinal vertical planes extending upward centrally of the respective pairs of rails a and a^1 , with the gears M and M¹ constituting one cooperative pair, and the gears M² and M³ constituting the other cooperative pair.

The gears M, M¹, M², and M³, being thus arranged, they are preferably secured to the 80 respective shafts m , m^1 , m^2 , and m^3 , which are rotatively mounted in suitable hangers m^4 secured to the under-side of the bed or platform A, with the gears of each pair extending upwardly to the proper distance above the 85 bed or platform to engage with the racks c^{13} , of the carriers as these latter are passed over them, and such gears so connected as to revolve in unison and in the same direction by spur-gears m^5 and m^6 , or m^7 and m^8 , with 90 which their respective shafts m and m^1 , or m^2 and m^3 are provided, coöperating with intermediate idler gears m^9 , m^{10} , and m^{11} , or m^{12} , m^{13} , and m^{14} , which in turn are respectively mounted in stands m^{15} or m^{16} that are 95 secured to the under-side of the bed or platform A, as shown.

With the gears M, M¹, M², and M³ thus operatively connected in pairs, these pairs are in turn operatively connected with each 100 other and with the shaft H, whereby to be caused to operate, not only in unison with respect to each other, but also with respect to the compacter F. To this end, I make use of the shafts N, O, and O¹ which are 105 respectively journaled in suitable bearings n , o , and o^1 secured to the under-side of the bed or platform A. Of these, the shaft N is preferably connected with the shaft H, through the intervention of the bevel gears n^1 and h^4 110 with which those shafts are respectively provided, while the shaft O is connected with the gear m^6 by a gear o^2 , and the shaft O¹ connected with the gear m^7 through the intervention of a gear o^3 .

With the pairs of gears M, M¹ and M², M³ thus connected with the shafts O, O¹, these latter shafts are connected with the shaft N whereby to be rotated in unison with it. The means by which this connection is effected may be of various kinds. The means however which I have selected for this purpose consists of sprocket wheels and sprocket chains; and, in order to provide for the rotation of the gears M, M¹, M², and M³, and 120 through them of the movement of the carriers C and C' at different rates of speed with respect to the rate of speed of the compacter, to thereby vary the density in which the sand may be compacted in the flasks, I find it de- 125 130

sirable to employ two sets of sprocket wheels and sprocket chains. To this end, I provide each of the shafts O and O¹ with two sprocket wheels P and P¹, of which the sprocket wheel 5 P on each is made somewhat larger than the sprocket wheel P¹, and connect these respective wheels with sprocket wheels R, R¹, R², and R³ on the shaft N, through the intervention of sprocket chains S, S¹, S², and S³, 10 which pass around them.

As thus connected the sprocket wheels R and R¹ are preferably secured upon a common hub R⁴ or otherwise secured together, while the sprocket wheels R² and R³ are 15 similarly connected by a hub R⁵; and in order, to provide for bringing either of these pairs of sprocket wheels into operation with the shaft N while carrying the other pair out of operation therewith, I preferably mount 20 both of these pairs of sprocket wheels loosely upon the shaft and provide each of their hubs R⁴ and R⁵ on its inner end with a clutch member r, which coöperates with a second clutch member T that is splined upon 25 the shaft N in such a manner as to be capable of movement longitudinally thereon to bring it into engagement with the clutch member r upon either of the hubs R⁴ or R⁵. With the parts thus constructed and arranged, either 30 of the pairs of sprocket wheels R and R¹, or the pairs R² and R³ may be brought into operation when the shaft N is in rotation, by bringing the clutch member T into engagement with its respective clutch member r, 35 and thereby the gears M, M¹, M², and M³ rotated at their faster or slower speeds, as one or the other of these pairs of sprocket wheels are locked to the shaft N by such clutch member T.

40 For sliding the clutch member T longitudinally upon the shaft N to bring it into engagement with the clutch member r of either of the pairs of sprocket wheels R, R¹ or R² R³ as may be desired, various expedients may 45 be adopted. I find it convenient however to employ for this purpose a lever U, which, pivoted in the bed of platform A by a suitable pivot u, and provided with a locking dog u¹ for engagement with suitable notches 50 u² formed in the curved segment U¹, engages at its other end with a circumferential groove t formed in the clutch member T, as shown.

With the gears M, M¹, M², and M³ thus connected with the shaft H, the movement of 55 the carriers along the rails a and a¹ will be accomplished whenever the shaft H is rotated; and in order to provide for the rotation of the gears M² and M³ in an opposite direction to that of the gears M and M¹, whereby the carriers on one pair of rails may be moved in one 60 direction and those on the other pair moved in the opposite direction, I interpose between the gears m⁷ and o³ an intermediate idler gear o⁴, supported upon a shaft o⁵, which is

secured to the under-side of the bed or plat- 65 form A by stands o⁶.

While the movement of the carriers C and C¹ upon the pairs of tracks a and a¹ is thus effected by the direct engagement of the gears M, M¹, M², and M³ with their racks c¹³, I 70 find it desirable to so construct these gears as to prevent the accumulation of sand on their peripheries intermediate their teeth m¹⁷, and to that end cut away the portions m¹⁸ on both sides of the gears between such 75 teeth, whereby to form their peripheries at those points as substantially sharp edges, as shown more particularly in Fig. 4.

The various parts being constructed and organized as above explained, a machine is 80 produced, in which, not only is the necessity for skilled labor obviated, but the machine rendered practically continuous in its operation, since all that is required in the automatic and continuous molding of the desired 85 articles is, to remove the successive flasks with their contained molds after they have passed under the hopper and compacter upon their carriers, and, after successively transferring such carriers from one pair of rails to 90 another, to supply empty flasks to them and pass them backward under the hopper and compacter in the opposite direction, and so on, each passage of a flask beneath the hopper and compacter on its carrier resulting in 95 the formation of a mold therein.

While in the foregoing I have described the best means contemplated by me for carrying my invention into practice, I wish it distinctly understood that I do not limit 100 myself thereto, as it is obvious that various modifications may be made in it and in its constituent parts without departing from its spirit and substantial characteristics. Again, while in the drawings I have shown and in 105 the foregoing described a mechanism for transmitting motion from the shaft H to the gear M, M¹, M² and M³ and for permitting of the change of the speed of these gears with respect to that of the shaft at pleasure, I make 110 no claim herein to such mechanism when separately considered, as the same forms the subject of application No. 460,380, which is a division of the present application, and which was filed by me in the United States Patent 115 Office October 31st, 1908.

Having thus described my invention and specified certain of the ways in which it is or may be carried into effect, I claim and desire to secure by Letters Patent of the United 120 States,—

1. The combination, with a hopper for receiving and delivering the sand, a series of carriers each adapted to carry a detachable and removable molding flask, and mechanism for automatically moving such carriers with their flasks beneath the hopper, of a compacter arranged within the lower end of 125

the hopper for feeding downward and compacting the sand into the successive flasks as they arrive beneath it, mechanism for imparting a rotary motion to the compacter, 5 devices arranged within the hopper for loosening up the sand and maintaining it in a loose condition during the operation of the machine, and mechanism by which the speed of movement of the carriers beneath the hopper 10 per may be varied; substantially as described.

2. The combination, with a hopper adapted for receiving and delivering the sand supplied to it, two series of carriers for receiving 15 and carrying detachable and removable molding flasks, and mechanism for moving the series of carriers with their flasks beneath the hopper in opposite directions, of a compacter arranged in the lower end of the 20 hopper for feeding downward the sand and compacting it in the flasks as they are carried beneath it, mechanism for supporting and imparting a rotary motion to the compacter provided with blades for loosening up 25 the sand supplied to the hopper and maintaining it in a loose condition when the machine is in operation, and mechanism by which the speed of movement of the carriers beneath the hopper may be varied; substantially 30 as described.

3. The combination, with a bed or platform provided with two pairs of rails, a hopper arranged and supported above such bed or platform, a series of carriers arranged to 35 move on each of the pairs of rails and adapted to carry molding flasks that are detachable and removable from such carriers, and mechanism for moving these series of flasks along their respective pairs of rails in opposite 40 site direction beneath the hopper, of a shaft extending downwardly through the hopper, and a compacter secured upon such shaft at the lower end of the hopper and constructed with two outwardly extending oppositely 45 and spirally arranged ribbon shaped flanges, a series of blades extending outwardly from said shaft and laterally inclined with respect to their paths of travel, and mechanism for rotating such shaft in unison with the movement of the carriers, and for varying the 50 speed of movement of the carriers with respect to such shaft; substantially as described.

4. The combination, with a body or platform 55 provided with two pairs of parallelly

disposed rails, a hopper mounted above such bed or platform, and a series of carriers provided with racks and mounted upon wheels that are adapted to move along such tracks, with the carriers adapted to receive and carry detachable and removable molding flasks; of two pairs of connected gear wheels adapted to engage with said racks and move the two series of carriers in opposite directions, and mechanism by which the pairs of gear wheels may be rotated at different rates of speed to accelerate or retard the movements of the carriers beneath the hopper, substantially as described.

5. The combination, with the hopper a 70 rotary compacter arranged in the lower end of such hopper, two series of carriers adapted to move beneath the hopper and compacter, and receive and carry detachable and removable molding flasks, racks with which 75 such carriers are provided; a shaft N and mechanism for rotating it in unison with the compacter, of two pairs of connected gear wheels for engaging with the racks on said carriers, a faster and slower motion transmitting mechanism between such shaft and the two pairs of connected gear wheels, and means whereby either one or the other of these motion transmitting devices may be brought into operation to move the said 80 pairs of gear wheels with their connected carriers at a faster or slower rate of speed with respect to the compacter as may be desired, substantially as described.

6. The combination, with a bed or platform provided with parallelly disposed rails, a hopper mounted above such bed or platform, and a series of carriers provided with racks and mounted upon wheels that are adapted to move along such tracks with 95 such carriers adapted to receive detachable and removable flasks, of mechanism for moving such carriers along said rails beneath the hopper, and scrapers carried by these carriers and arranged to coöperate with the rails 100 for removing sand and other obstructions from such rails, substantially as described.

In testimony whereof I have hereunto set my hand in the presence of two witnesses this 30th day of December, 1907.

JOHN G. MORRISON.
